United States Patent Office

Des. 227,707
Patented July 10, 1973

227,707

LINE PRINTER

Norman Allen Cargill, Warminster, Pa., assignor to
Peripheral Dynamics, Inc., Morristown, Pa.

Filed Mar. 16, 1972, Ser. No. 235,471

Term of patent 14 years

Int. Cl. D18—02

U.S. Cl. D64—11 R

Fig. 1

Fig. 2

*Fig. 3**Fig. 4**Fig. 5*

FIG. 1 is a perspective view of a line printer showing my new design;

FIG. 2 is a top plan view thereof;

FIG. 3 is a front elevation thereof;

FIG. 4 is a right side elevation thereof; and

FIG. 5 is a rear elevation thereof.

I claim:

The ornamental design for a line printer, as shown.
